UNITED STATES PATENT OFFICE.

CLIFTON CHISHOLM, OF CLEVELAND, OHIO, ASSIGNOR TO THE AMERICAN MULTIGRAPH COMPANY, OF CLEVELAND, OHIO, A CORPORATION OF OHIO.

AUTOMATIC STOP MECHANISM FOR ADDRESSING MACHINES.

Application filed November 20, 1920. Serial No. 425,476.

To all whom it may concern:

Be it known that I, CLIFTON CHISHOLM, a citizen of the United States, residing at Cleveland, in the county of Cuyahoga and State of Ohio, have invented a certain new and useful Improvement in Automatic Stop Mechanism for Addressing Machines, of which the following is a full, clear, and exact description, reference being had to the accompanying drawings.

This invention relates to mechanism adapted to form a part of an addressing machine and operate to stop the operation upon the arising of some contingency, for instance, the failure of the paper to properly feed or the magazine of address plates becoming empty.

One of the objects of the invention is to make such mechanism simple and at the same time efficient, and readily operable for the thinnest paper used as well as for the heavier grades. In effecting this I arrange the paper, feeding parts so that they may throw into action power mechanism to shift a controlling clutch.

Another object is to enable practically the same mechanism to throw out the controlling clutch either when the paper fails to feed or the magazine becomes empty.

The invention is illustrated in an approved form in the drawings hereof, and is herein-after more fully explained and its essential novel features summarized in the claims.

In the drawings Fig. 1 is a sectional side elevation of the machine; Fig. 2 is a front elevation showing a portion in section; Figs. 3 and 4 are details illustrating the position of one of the paper engaging rolls which control the clutch, first where the paper is absent, and second where the paper is present.

Referring by numerals to the parts shown in the drawings, 10 indicates the bed of the machine, and 11 one of a pair of suitable frame standards rising therefrom.

In these standards are mounted a shaft 12 for the paper feeding drum 13 and shaft 14 on which the platen 15 is journalled. 20 indicates a vertical magazine for address plates, a number of which are shown at 21. These plates descend by gravity, and the lowermost one is engaged and fed to the right (Fig. 1) by conveyer chains 24 running over sprockets 25 on a shaft 26 and over other sprockets 27 on the shaft 14 which is suitably geared with the shaft 12. These chains have

lugs 29 adapted to engage the plates and feed them to the impression members. The chain may be kept taut by adjusting the position of the bearing 28 of the shaft 26. 30 and 31 indicate suitable inking rollers adapted to ink the characters on the address plates as they pass between the roller 31 and supporting rollers 32.

The mechanism above described is shown incidentally to illustrate the operation of the automatic stop mechanism which forms the subject matter of this application. The particular paper feed drum shown is described more fully and claimed in my co-pending application No. 420,415, filed Oct. 29, 1920. As here shown it comprises, beside the body 13, a pair of segmental yielding platen members 40, mounted on the body, and a pair of rings 41 at the end of the body and having their outer periphery flush with the periphery of the segmental members. Co-operating with these rings are rollers 50 and 51 which have their axes parallel with the shaft 12 and project thru openings in a stationary guard plate 52.

The paper is fed by mechanism—not shown—but which may be in accordance with my patent No. 1,285,623, issued November 26, 1918, from a position above the paper feeding drum downwardly toward the left in Fig. 1, between the drum and the shield 52. The paper when passing between the shield and drum is held against the drum by the rollers 50 and 51, acting successively on the paper until it comes above the impression platen. At this time one of the segmental members 40 is above the platen 15 and one of the plates is in a similar position, so that the plate and paper are fed together toward the right in Fig. 1 between the yielding pressure platen 15 and one of the yielding segmental platens 40.

To cause the operation of the paper feed and conveyor to stop, in case of failure of either the paper or plates, I drive the shaft 12 by means of a clutch which is thrown out by the mechanism about to be described. Fig. 2, shows at 60 a driving pulley loose on the shaft 12, and at 61 a shiftable clutch splined to the shaft and adapted to couple the pulley with it, or leave it disconnected therefrom. 62 indicates a suitable shipper lever for shifting this splined clutch collar. This shipper lever is preferably equipped with a handle 64 for manual operation whenever desired; 110

for the automatic operation it carries a blade 65 extending into a peripheral notch 71 in a rotary but longitudinally shiftable shaft 70, as shown in Fig. 2. This figure shows 5 the position of the parts when the shaft has been shifted toward the right to disengage the clutch. Movement to this position is effected by actuation of the paper feeler mechanism to be described.

10 Pivots mounted on a stationary frame rod 75 are a pair of arms 76 and 76^a which are bent as shown at 76^b in Fig. 1 and carry at their ends rollers 77 adapted to ride on the rings 41. In these rings are formed segmental grooves 45 which in the rotation of the drum come opposite the rollers 77. Now, if paper is present bridging the grooves 45, the rollers will be thereby held out of the grooves in substantially the same position 15 they occupy when other portions of the drum are opposite them. Fig. 4 indicates at A a sheet of paper, or an envelope, on the drum bridging the grooves 45 and shows how this maintains the roller 77 in 20 its normal position.

If there is a failure of the paper to properly feed, then when the uncovered groove 45 comes opposite the roller 77, the roller will at once drop by gravity into the groove 30 45, as shown in Fig. 3. Each arm 76, 76^a carries a pin 79. These pins are normally idle, but when the roller drops into the groove the pin stands in the path of the crown cam 80 or 80^a on the rotary shaft 70.

35 Thereupon the continued rotation of this shaft causes the cam to engage the pin and draw the shaft to the left as one faces the machine, which is into the position shown in Fig. 2. This movement swings the shipper lever to disengage the clutch, which thereafter remains disengaged until restored by manual movement of the shipper lever.

45 The shaft 70 being rotated by power, it will be seen that the feeler arms do not of themselves perform the work of disengaging the clutch. They simply move into the paths of the power driven cams, which effect the operation. This allows the feeler 50 arms to be made light enough to be supported in their inactive position by the thinnest paper used bridging the recess; at the same time the power mechanism has ample force to disengage the clutch.

55 It is desirable that the mechanism be arranged to feed two envelopes for each rotation of the drum 13, or one envelope, or a sheet of paper, when the same are of larger size. To accomplish this I provide the two
60 platens 40, and I arrange them so that one or both of them may be presented to the successive address plates; that is to say, I provide change speed gearing adapted to be shifted to cause the drum 13 to make either
65 one rotation or a half rotation for each ad-

dress plate fed. Such a system is shown, described and claimed in my prior application No. 371,722, filed April 6, 1920. In the present invention I provide two paper feeding arms 76 and 76^a, and I arrange one of 70 these to have a possible operation only once for each rotation of the drum 13, while the other may possibly operate twice for each rotation. This arrangement and the mechanism for rendering only one arm or the other active, in accordance with the condition of the change speed gearing, will now be described. 75

As shown in Fig. 2, the shaft 12 which carries the printing drum also serves to drive the conveyer chains thru variable gearing. In Fig. 2, 90 and 91 indicate meshing gears of the same size on the shafts 12 and 14. 92 and 93 indicate meshing gears on these shafts, the latter gear having twice the diameter of the former. The gears 91 and 93 are tight on the shaft 14, which operates the conveyer chains, the impression platen 15 being loose on this shaft. The driving gears 90 and 92 are both loose on the shaft 12, and either of them may be clutched to this shaft by a sliding key 95 which occupies a keyway in the shaft 12 and has a radially projecting end adapted to engage a notch 96 in the hub of the gear 90, or a notch 97, in the hub 92, as shown in Fig. 3 when the key projection occupies an intermediate position both gears are out of action.

To shift the key 95, I form a projection 100 at its outer end, which occupies a peripheral groove in a bushing 100 carried by a shiftable bracket 101. This bracket is mounted on a sliding rod 102. On this rod are a pair of collars 103 and 104 having inclined edges, as shown in Fig. 2. These collars are adapted to clear or engage their respective arms 76, 76^a, and are so positioned that when one collar is engaging its arm the other collar is free therefrom, as shown in Fig. 2.

If the bracket 101 be moved to the left from its idle position shown in Fig. 2, the gear 92 will be locked to the shaft and the collar 103 will be brought beneath the arm 76, the collar 104 clearing the arm 76^a. The arm 76 and its roller 77 are thus held inactive, but the arm 76^a and its roller are active. The drum ring which co-operates with the roller of this arm has one arcuate groove 45, so that but one test will be made for the presence or absence of paper for each rotation of the drum 13. When the gear 92 is active, as now supposed, the conveyer chain shaft 14 will make a half rotation for each rotation of the drum. Each half rotation of the shaft 14 brings a fresh plate to the printing position, since the conveyer chain lugs 29 are spaced a distance corresponding to half the periphery of the 130

sprockets on the shaft 14 which carry the chains. Accordingly each rotation of the shaft 12 feeds either one large envelope or a sheet of paper, and one test is made for its presence or absence.

If the bracket 101 be drawn toward the right from the position shown in Fig. 2, the gear 90 will be coupled to the shaft 12 and at the same time the collar 104 will raise the arm 76^a into inactive position and the arm 76 will become active being freed by the removal of the collar 103. With this gear connection there will be one rotation of the shaft 14 for each rotation of the shaft 12. As the plate-feeding lugs 29 on the conveyer chains are spaced a distance corresponding to half the periphery of the sprockets on the shaft 14, it follows that each rotation of this shaft will bring two plates to printing position, and this would require two pieces of paper, or envelope, to be printed. This is the coupling which I employ for ordinary envelopes, one being printed when one of the segmental platens 40 is active and the other when the other platen 40 is active. The arm 76 which is active under these circumstances has its roller 77 riding on a ring 41 which carries two arcuate grooves 45, as shown in Fig. 1, so that in this case the two tests are made for each rotation of the drum.

It will be seen from the above description that my stop mechanism is automatically positioned in correspondence with the change in the gearing when the machine is changed from ordinary envelopes to large size envelopes or paper, or vice versa, the simple shoving in or pulling out of the bracket 101 accomplishing both the adjustment of the gearing and of the throw-out mechanism in a very simple manner.

The power may be transmitted to the rotating shaft 70 from any suitable part of the machine. I find it very convenient to provide a pinion 105 on the shaft meshing with a broad idler 106, which meshes with the gear 90. When the shaft 12 is active the gear 90 is always rotating, being either keyed to it or driven by the train of gears 91 and 93 from the gear 92. The breadth of the idler 106 allows the pinion 105 to shift longitudinally, while maintaining its mesh with the idler.

To enable the same clutch-shifting mechanism to stop the operation when the supply magazine becomes empty, I provide an arm 110 pivoted to the side of the magazine at 111 and adapted to lie against the forward edge of the plates, and to the upper end of this arm I pivot a link 112 which connects at its rear end with a rock arm 113 connected with a rock arm 114 loosely mounted on the rod 75, and having a pin 115 adapted to be moved into or out of the path of a crown cam 116 on the shaft 70.

Ordinarily the mechanism just described is idle, but whenever the magazine becomes empty, the arm 110 becomes thereby freed from restraint, and a spring 118 swings the upper end of this arm forwardly. This lowers the arm 114 to cause the pin 115 to stand in the path of the cam 116. Accordingly the rod 70 as it rotates is cammed in the direction to move the shipper lever to disengage the clutch in the manner already described.

Having thus described my invention, I claim:—

1. In an addressing machine, the combination, with a rotary paper support having a recess, a member adapted to move into the recess when the paper is absent, a stop movable by such member, a power driven rotary cam adapted to engage such stop and be axially shifted thereby as the cam rotates, and mechanism actuated by such shifting of the cam to effect a stoppage in the operation of the machine.

2. In a machine of the character described, the combination, with means for guiding and feeding paper, of a feeler bearing on the paper and adapted to be opposite a recess on the other side of the paper, a clutch, a shiftable cam adapted to disengage the clutch, and an abutment for the cam carried by said feeler.

3. In a machine of the character described, the combination, with means for guiding the paper, of a feeler adapted to bear on the paper opposite a recess, a clutch, a shiftable rod adapted to operate the clutch, a shiftable cam for moving said rod, and an abutment for the cam carried by said feeler.

4. The combination, with means for guiding and feeding paper, of a feeler adapted to bear on the paper opposite a recess on the other side of the paper, a clutch, a longitudinally shiftable rod for operating the same, a crown cam on the rod, and an abutment for the cam positioned by the feeler.

5. The combination, with means for guiding and feeding paper, of a feeler adapted to bear on the paper opposite a recess, a clutch, a longitudinally movable rod for shifting the clutch, gearing for rotating the rod, a crown cam on the rod, and an abutment for the cam adapted to be positioned by the feeler.

6. The combination with a paper guide having a recess, a pivoted arm adapted to coact with paper on the opposite side thereof from the recess, a pin on said arm, a crown cam adapted to be engaged by said pin and moved thereby, or cleared, according to whether the recess is covered or uncovered, a clutch for controlling the operation, and a connection between the clutch and the crown cam.

7. In a machine of the character described, the combination, of a rotary drum, means for feeding, as desired, either one or two articles for each rotation of the drum, a 5 throwout device having two feelers, one operative once a rotation, and the other operative twice a rotation, and means for rendering one or the other feelers active according to whether the mechanism is feeding 10 one or two articles for each rotation, a power driven clutch shifter, and an abutment therefor positioned by said feelers.
8. In a machine of the character described, the combination, of a platen, a rotary paper 15 feeding drum coacting therewith, and having two impression surfaces, conveyor means for feeding plates between the drum and platen, changeable gearing between the drum and the conveyor means to enable 20 either one or two plates to coat with the drum, a clutch for stopping the operation, two feelers coacting with the drum, one arranged to operate once a rotation and the other twice a rotation, and a device for 25 simultaneously shifting the gearing and rendering the corresponding feeler active and the other inactive, shiftable cams moved by engagement with said feelers, and a connection between said cams and the clutch.
9. In an addressing machine, the combination, of a supply magazine, a conveyer, an arm bearing against a plate in the magazine, a clutch for operating the conveyer, a longitudinally movable rotary shaft for 30 releasing the clutch, a crown cam on said shaft, and means operated by the movement of said arm when the plate is absent for placing a stop in the path of said cam.
10. In an addressing machine, the combination, of a supply magazine for address 35
- plates, lever mechanism mounted to engage the edges of one or more of the plates adjacent the discharge end of the magazine and be restrained thereby, a clutch, a longitudinally shiftable rod adapted to uncouple 45 the clutch, and means connected with said lever mechanism for causing the rod to shift when the lever mechanism moves consequent upon the absence of the plates in the magazine. 50
11. In an addressing machine, the combination, of a supply magazine, a conveyer, a pair of impression members to which the conveyer may carry plates from the magazine, one of said impression members being 55 adapted to act as a paper feeding roller, mechanism operated by the absence of paper on the roller, a clutch adapted to control the movement of both the paper roller and the conveyer, a movable member adapted 60 to release said clutch and having a cam, and means movable into the path of the cam by either of the mechanisms mentioned.
12. The combination of a rotary shaft, a paper carrying drum thereon, a rotary controller mechanism for controlling rotation of the drum, power transmitting mechanism connecting said shaft and said controller mechanism, a power driven mechanism, a 65 clutch adapted to connect the power driven mechanism to said shaft, and a lever member coacting with the drum to enter a recess therein in the absence of paper on the drum, said lever reacting on the controller mechanism to cause the latter to disconnect the shaft from the power driven mechanism. 70
- In testimony whereof, I hereunto affix my signature.

CLIFTON CHISHOLM.
